CONTACT EXPOSURE MACHINE OR SIMILAR ARTICLE

Joseph Palma, Jr., River Forest, Ill., assignor to Ditto
Incorporated, Chicago, Ill., a corporation of Illinois

Filed Mar. 30, 1960, Ser. No. 59,936

Term of patent 14 years

(Cl. D61—1)

Figure 1 is a perspective view of a contact exposure machine, or similar article, showing my new design;

The essential features of my new design are shown in solid lines in the drawing.

I claim:

The ornamental design for a contact exposure machine or similar article, substantially as shown and described.
